DESIGN FOR A SURFACE MOUNTED FLUORESCENT LAMP FIXTURE

Pasquale J. Lepore, Somerville, Mass.

Application June 14, 1944, Serial No. 113,998

Term of patent 14 years

(Cl. D48—23)

To all whom it may concern:

Be it known that I, Pasquale J. Lepore, citizen of the United States, residing at Somerville, in the county of Middlesex and State of Massachusetts, have invented a new, original, and ornamental Design for a Surface Mounted Fluorescent Lamp Fixture, of which the following is a specification, reference being had to the accompanying drawing, forming part thereof,

Figure 1 is a perspective view of a surface mounted fluorescent lamp fixture showing my new design; and

Figure 2 is a side elevational view of the same.

I claim:

The ornamental design for a surface mounted fluorescent lamp fixture, as shown.

PASQUALE J. LEPORE.
